UNITED STATES PATENT OFFICE.

HAKON SIGVART LARSEN, OF CHRISTIANIA, NORWAY.

CORK-CUTTING MACHINE.

SPECIFICATION forming part of Letters Patent No. 396,882, dated January 29, 1889.

Application filed June 21, 1888. Serial No. 277,785. (No model.) Patented in Norway August 27, 1887.

To all whom it may concern:

Be it known that I, HAKON SIGVART LARSEN, a subject of the King of Norway, and a resident of Christiania, in the Kingdom of Norway, have invented certain new and useful Improvements in Cork-Cutting Machines, (for which I have received Letters Patent in Norway, dated August 27, 1887;) and I do hereby declare that the following is a full, 10 clear, and exact description of the same.

My invention consists in a cork cutting and finishing machine so constructed that the necessary hand-work consists only in placing the cork blocks in a certain position on the 15 machine, while the operations of transporting said blocks to the cutting-tool, the accurate adjustment of them in front of said cutting-tool, and the rotating of them, whereby they are given their cylindrical form, are performed by the automatic movements of the 20 machine.

The machine comprises four groups or series of mechanism—namely, a cutting-tool, an apparatus for imparting a rotary motion to 25 the cork blocks, an apparatus for catching the cork blocks and conveying them to the knife and the rotating mechanism, and an apparatus for taking the cork blocks from the spot where they are deposited by the operator 30 and carrying them to the proper position.

The invention will be understood on reference to the accompanying drawings, in which—

Figure 1 represents a plan view of a machine constructed according to my invention. 35 Fig. 2 is a vertical section taken in the line $x-x$ of Fig. 1. Fig. 3 is a vertical section taken in the line $y-y$ of Fig. 1.

In Figs. 2 and 3 some of the parts are omitted or only shown in outline, so as not to interfere with the clearness of the drawings.

The cutting-tool consists of a circular knife, K, carried by one end of the main shaft A, which may be rotated by hand or by any suitable motive power. From this shaft A the motion is transferred by a belt and pulleys to the shaft B, which is journaled on the top of the frame C of the machine. From the shaft B the several periodical movements are imparted by means of gearing and cam-wheels or the like to the different portions of the 45 machine.

The transporting apparatus on which the cork blocks are placed is designated by the letter G. It consists of a ring, 1, of L-shaped cross-section, fitted in a guide, 2, mounted on the frame C, Figs. 1 and 2. Said movable ring 1 is provided on the upper surface with pins 3, placed at such distances apart as to admit a cork block between two of them. The periphery of the ring or wheel 1 is provided with a number of notches corresponding with the number of pins, and has an intermittent rotary motion imparted to it by means of a spring-pawl, 4, carried by one end of a lever, 5, which is pivoted at 6 and has its other end bearing against a cam-wheel, 7, on the shaft B, said lever being held in contact with the cam-wheel by a spring arranged in any suitable manner. When the cam-surface of the wheel 7 forces the short end of the lever outward, the pawl 4, carried by the other end, rotates the transporting-wheel a distance equal to the distance between two of the notches. The pawl 4 has its pivot 8 arranged in a slot, 9, in the end of the lever 5, and may be adjusted in either direction by means of the set-screws 10.

To the inner and outer surfaces of the guide 2 are attached two guard-plates, 11 and 12, which extend from the point where the cork blocks are placed on the wheel to the point where they are pushed into the catching-apparatus or carrier-wheel H.

The cork blocks are pushed from the transporting-wheel into the catching-wheel H by means of a plate, 13, attached to one end of a rod, 14. The front end of this rod has a bearing in a guide, 15, and its other end is connected to an arm or lever, 16, by being passed through a sleeve or head, 17, pivoted at the upper end of said lever and held in place by means of two nuts which serve as adjusting-nuts, so that the plate 13 may be adjusted at a greater or less distance from the catching-wheel H. A spring, 18, surrounds the rod, with its ends bearing against the guide 15 and one of the nuts, respectively, and thus holds the plate 13 in proper position.

The movement of the plate 13 toward the 100 catching-wheel is imparted by a rock-shaft, 21, which has at one end an arm, 20, bearing against a cam-wheel, 19, on the shaft B, the lever 16 being attached to the other end of

said rock-shaft 21. When the cam on the cam-wheel strikes the arm 20, the movement is imparted to the rod 14.

During the movement of the plate 13 the 5 cork blocks are held against said plate by means of a flat spring, 22, the detailed arrangement of which is hereinafter more particularly described.

The catching-wheel or carrier-wheel II is 10 composed of two disks or wheels, 26 and 27, mounted on the same shaft, 25. The disk 26 contains the mechanism by means of which the cork blocks are caught, securely held, and carried up to the cutter, and the other disk, 15 27, contains a set of short spindles with flanges, against which the cork blocks are pressed by the disk 26, and which spindles, with chucks, are rotated by means of the turning apparatus F, arranged at the side of 20 the wheel 27, which is periodically connected with the said spindles, so that the cork blocks are rotated in front of the cutter or knife K.

The disk 26 is provided with a series of 25 holes near its periphery and parallel with the axis of rotation, and in each of these holes, which are drilled with an offset, is fitted from the inner side of the disk a short spindle, 28, with a flange, 29, provided with spurs, serving as a prong-chuck, and from the other side 30 of the disk are inserted spring-boxes 30. The said spindles 28 are connected to the spring-boxes by means of studs 31, screwed into the inner end of the spindles, and the heads of which are pressed toward the bottom of the 35 spring-boxes by means of springs 32. As the spring-boxes are prevented from moving to the right, the spindles and chucks will have a tendency to move to the left. From the outside of the spring-boxes extend pins 33 40 through slots 34 in the periphery of the wheel 26, by means of which the boxes may be moved in their axial direction.

On the outside end surface of the disk 26 are arranged arms 35, one for each spring-box, pivoted at one end, 36, with the other end long enough to reach in front of the holes in which the spring-boxes are inserted. The arms are held in place and guided by keepers 37, Figs. 1 and 2.

50 Co-operating with the spring-boxes and stopper-arms above mentioned are the levers 38 and 39, Fig. 2, carried by a shaft, 40, the lever 38 being about midway of the length of the shaft and the lever 39 at one end. The 55 other end of the shaft 40 is provided with an arm, 41, to which is connected a rod, 42, Figs. 1 and 3, actuated from the cam-wheel 43 on the shaft B. The rod works in a guide, 44, and has an upright bend, 45, behind the cam-wheel, against which it is pressed by a spring, 45^s. The object of these devices is to catch and release the cork blocks at the proper times. As will be seen in Fig. 2, the upper 60 ends of the levers 38 and 39 terminate in front of two of the spring-boxes—namely, the one belonging to the spindle, that catches the cork blocks, and the one next below, where the

corks are turned. When the levers move inward to the disk, they strike the ends of the spring-boxes and drive them inwardly. The 70 result of this will be, as far as regards the arm 38, that the spring 32 will act upon the stud 31, pressing the spindle with the chuck into the cork block (just at that moment held by the spring 22 and the plate 13) between 75 the two disks, and instantaneously the stopper-arm 35 will drop down and lock the spring-box into the hole, so that it cannot again issue therefrom before the cork has been cut. It will then be released by the arm 39, which 80 will press the spring-box at the time in front of the arm slightly inward. The arm 35, which was held by friction, will then drop down and allow the box to project out through the hole, thereby releasing the spring 32, and 85 with it the spindle 28 and the cork. The cork is prevented from adhering to the spurs of the chucks by means of pin 33, working in the slot 34. When the wheel moves the next step, this pin will strike a wedge, 33^a, placed underneath the disk, and be forced with the box and the spindle to the right, so that the flange 29 will come close to the side of the disk and the cork may drop down through a hole in the frame into a suitable receptacle. To further insure that no cork shall adhere to the chucks, a rod, 33^b, Fig. 2, is connected to the 90 same lever, 16, that pushes the blocks into the catching-wheel. When the said lever moves against the wheel, the rod 33^b will also follow, 95 and in case a cork should be hanging in the wheel push it down.

The disk 27, which is mounted on the same shaft with the disk 26, and accordingly moves together with it, has near its periphery in 105 line with the spindles in disk 26 a series of short spindles, 46, provided on the inner side with prong-chucks and on the outside with coupling-clutches 47, with which the coupling-clutches on the turning apparatus F periodically engage.

When a cork block has been pushed between the two disks 26 and 27, the machine is so timed that the lever 38 will press the spindle 28 into the cork, which will then be 110 held between the two prong-chucks.

The object of the spring 22 is to accurately center the block between the chucks. The plate 13 being adjusted by the adjusting-nuts, the said spring will hold the blocks tightly 115 up to the plate and keep them there until they are caught by the chucks. To release the spring, so that it shall not, when the block is taken upward by the wheel, snap outwardly, it is attached to one end of a pin, 23, boxed 120 on the frame C, which pin has on its other end an arm extending upward on the outside of the disk 27, where it rests against the coupling-clutches 47 of the spindles. At the 125 moment the wheel moves a step forward the coupling-clutch will pass the end of the said arm and the spring will be released until the next clutch touches the arm.

The movement of the catching or carrier

wheel H, which is periodical, and with such a long stop between each step that a cork may be turned and cut during this standstill, is imparted to it through the pivoted pawl 48, 5 engaging with notches in the disk 26, the number of notches being the same as the number of spindles. The pawl 48 is pivoted to the upper end of a rod, 49, working vertically in a guide, 50, on the frame C. This 10 rod is suspended in a hanger, 51, (the length of which may be adjusted by means of a right and left nut, as indicated in the drawings,) on one end of a lever, 52, the other end of which bears against a cam-wheel, 53, on the 15 shaft B, said lever imparting a vertical motion to the aforesaid pawl 48, in order to partially rotate the wheel H, after which the lever falls of its own weight.

From the foregoing description it will easily 20 be understood how the cork blocks one after another will be pushed into the carrier-wheel H, taken up by this wheel, and carried forward till they reach the front of the cutting-tool or rotary knife K. Having reached to this 25 position, they have to be rotated, so that the cutting-edge may give them their cylindrical form. This is performed by means of the turning apparatus F. This turning apparatus consists of a spindle, 54, resting in a stand, 30 55, on the frame, and on which is mounted a tooth-wheel, 56, with an extended hub. The spindle is axially movable in this hub, but must follow the tooth-wheel in its rotation, (a projection from the tooth-wheel working into 35 an axial groove in the spindle, or vice versa.) The tooth-wheel is worked from the shaft B through the gears D and E. The extended hub rests on both sides in bearings in a stand on the frame, and the tooth-wheel is thereby 40 prevented from following the spindle in its longitudinal movement. The spindle will, according to this, constantly revolve, while the longitudinal movement is imparted to it periodically from the shaft B by means of a 45 cam-wheel, 58, acting on a lever, 59, pivoted on the frame, bearing near its mid-length against the cam-wheel and at its top provided with a fork that works in a groove or between two collars, 60, on the end of the spindle. By 50 these means the spindle is moved outwardly from the carrier-wheel toward the left-hand side of the drawing, while it is held against the same by means of a spiral spring, 61, surrounding the spindle between the bearing 57 55 and a collar, 62, on the spindle. The machine is so timed that when a cork has come in front of the knife the cam on the cam-wheel 58 will turn off from the lever 59, and accordingly the spindle will be taken inwardly by 60 the spring 61, and the coupling-clutch 63, mounted on the end of the spindle, will engage the coupling-clutch 47 on the spindle in wheel 27, by which the cork block to be cut is held. As soon as the cork has been cut, 65 (namely, rotated once,) the cam 58 will again take the spindle outwardly and the coupling-clutches will be disengaged, after

which the carrier-wheel moves another step forward and the operation is repeated.

The machine has a circular knife, K, 70 mounted on the main shaft A, the rotation of which knife greatly increases the effect of the cutting and facilitates the work of the machine. To further facilitate the cutting, the knife is made so thin that it is necessary to 75 mount it on a disk, 65.

To enable the machine to cut different sizes of corks, the knife is made movable in the direction of its axis. This of course may be arranged in different ways. As shown in the 80 drawings, the main axle A is journaled in bearings or boxes carried by straps underneath the frame. One of these straps—the front one, 66—is arranged so that it may swing on one of its bolts, 69, while the other 85 bolt, 67, Figs. 1 and 3, is inserted in a slot, 68, in the frame. When the strap 66 is swung either way, the shaft will be moved axially and the knife will be moved a greater or less distance from the center of the turning spindle. The boxes 71 are held to the straps by 90 means of pins, so that they may swing laterally. That the knife also may be adjusted vertically, the forward strap is on one side provided with a set-screw, 70, by means of 95 which and the bolt 67 the strap may be raised or lowered.

In order to keep the edge of the knife sharp, grinding-rollers may be attached to the frame, touching the sides of the knife, and thereby 100 grinding the edge while rotating.

What I claim as new, and desire to secure by Letters Patent, is—

1. In an automatic cork-machine, the combination, with a turning apparatus, F, consisting of an axially-movable spindle, 54, constantly rotated by suitable gearing, of a carrier-wheel, H, consisting, essentially, of two disks, between which the cork blocks are held, and one of which disks, 27, is provided with 105 a number of spindles provided on one side with a prong-chuck and on the other with a coupling-clutch; said turning spindle 54 being also provided with a coupling-clutch, which coupling-clutches are engaged with 110 each other at intervals by means of the axial movement of the turning spindle, and said disk being mounted on an axle having an intermittent rotary motion at intervals corresponding with the number of spindles in the 115 disk, substantially as herein described.

2. In an automatic cork-machine, a carrier-wheel, H, composed of two disks mounted on the same shaft, one of said disks, 27, having a number of spindles at equal distances from 125 each other near the periphery of the disk, the axes of which spindles are parallel to the axis of the disks, said spindles running through the disk, and having on the inside a prong-chuck and on the outside a coupling-clutch, 130 and the other disk, 26, having also near its periphery, opposite to the aforesaid spindles, a corresponding number of spindles with prong-chucks, in combination with spring-

boxes inserted from the outer side of said disk, a spring in said spring-boxes acting upon the end of the spindles, and the spring-boxes being at intervals pushed to their inmost 5 position and held there by means of stopper-arms 35 on the outside of the disk; being allowed at intervals to issue from the holes in which they are fitted, and thereby releasing the spring, said intervals being fixed by the 10 movements of two arms, 38 and 39, periodically touching the ends of the spring-boxes, and both disks having at intervals an intermittent rotary movement imparted in one direction, according to the number of spindles at 15 the periphery, substantially as herein described.

3. In combination with the carrier-wheel of an automatic cork-machine, as specified in claim 2, the pin 33 on the spring-box 30, working in a slot, 34, in the periphery of the disk 26, in combination with an angle-piece, 33^a, acting as a wedge against the pin 33 under 20

the revolution of the carrier-wheel, substantially as herein described.

4. In an automatic cork-cutting machine 25 provided with a carrier-wheel, H, composed of two disks mounted on the same shaft, one of said disks having a number of spindles provided with prong-chucks and coupling-clutches and the other disk having a corresponding number of spindles with prong-chucks acting in connection with spring-boxes, the combination, with said carrier-wheel, of a transporting-wheel, G, and devices connected therewith for pushing the cork blocks into 30 the carrier-wheel, substantially as herein described.

In witness whereof I have hereunto set my hand in presence of two witnesses.

HAKON SIGVART LARSEN.
